Primary Examiner — Sheryl Lane*Assistant Examiner* — Ieisha N Price(74) *Attorney, Agent, or Firm* — George L Williamson(57) **CLAIM**

The ornamental design for a reversible saddle for driveline coupler, as shown and described.

DESCRIPTION

FIG. 1 is a top perspective view of a reversible saddle for driveline coupler showing my new design;

FIG. 2 is a bottom perspective view thereof;

FIG. 3 is a top plan view thereof;

FIG. 4 is a front side elevational view thereof, the rear side elevational view being identical;

FIG. 5 is a bottom plan view thereof;

FIG. 6 is a left side elevational view thereof, the right side elevational view being identical; and,

FIG. 7 is a top perspective view thereof.

The broken line showing of a portion of a driveline coupler and drive shafts assembly illustrates environmental structure and forms no part of the claimed design.
